(57) **CLAIM**

The ornamental design for a mobile phone, as shown and described.

DESCRIPTION

FIG. 1 is front view of the mobile phone showing our new design.

FIG. 2 is a rear view of the mobile phone of FIG. 1.

FIG. 3 is a left side view of the mobile phone of FIG. 1.

FIG. 4 is a right side view of the mobile phone of FIG. 1.

FIG. 5 is a top plan view of the mobile phone of FIG. 1.

FIG. 6 is a bottom plan view of the mobile phone of FIG. 1.

FIG. 7 is a front, left perspective view of the mobile phone of FIG. 1.

FIG. 8 is a front, right perspective view of the mobile phone of FIG. 1.

FIG. 9 is a front view of the mobile phone of FIG. 1 in an open state.

FIG. 10 is a rear view of the mobile phone of FIG. 1 in the open state.

FIG. 11 is a left side view of the mobile phone of FIG. 1 in the open state.

FIG. 12 is a right side view of the mobile phone of FIG. 1 in the open state.

FIG. 13 is a top plan view of the mobile phone of FIG. 1 in the open state.

FIG. 14 is a bottom plan view of the mobile phone of FIG. 1 in the open state.

FIG. 15 is a front, left perspective view of the mobile phone of FIG. 1 in the open state.

FIG. 16 is a rear, left perspective view of the mobile phone of FIG. 1 in the open state.

FIG. 17 is an enlarged view of the portion encircled and marked with A FIG. 1.

FIG. 18 is an enlarged view of the portion encircled and marked with B in FIG. 1.

FIG. 19 is an enlarged view of the portion encircled and marked with C in FIG. 2.

FIG. 20 is an enlarged view of the portion encircled and marked with D in FIG. 2.

(Continued)

FIG. 21 is an enlarged view of the portion encircled and marked with E in FIG. 3.

FIG. 22 is an enlarged view of the portion encircled and marked with F in FIG. 4.

FIG. 23 is an enlarged view of the portion encircled and marked with G in FIG. 7.

FIG. 24 is an enlarged view of the portion encircled and marked with H in FIG. 8.

FIG. 25 is an enlarged view of the portion encircled and marked with M in FIG. 5.

FIG. 26 is an enlarged view of the portion encircled and marked with N in FIG. 5.

FIG. 27 is an enlarged view of the portion encircled and marked with O in FIG. 9.

FIG. 28 is an enlarged view of the portion encircled and marked with P in FIG. 9.

FIG. 29 is an enlarged view of the portion encircled and marked with Q in FIG. 10.

FIG. 30 is an enlarged view of the portion encircled and marked with R in FIG. 10.

FIG. 31 is an enlarged view of the portion encircled and marked with S in FIG. 11.

FIG. 32 is an enlarged view of the portion encircled and marked with T in FIG. 12.

FIG. 33 is an enlarged view of the portion encircled and marked with U in FIG. 13.

FIG. 34 is an enlarged view of the portion encircled and marked with V in FIG. 13.

FIG. 35 is an enlarged view of the portion encircled and marked with X in FIG. 15; and,

FIG. 36 is an enlarged view of the portion encircled and marked with Y in FIG. 16.

The broken lines in FIGS. 1-36 show portions of the mobile phone, and are used to encircle and mark portions of the mobile phone, and form no part of the claimed design.

The dash-dot lines in FIGS. 1-36 show boundaries of the claimed design and form no part of the claimed design.

1 Claim, 30 Drawing Sheets
